SUPPORT FOR LAMPS

Max Lager, New York, N. Y.

Application April 12, 1937, Serial No. 136,358

2 Claims. (Cl. 240—52)

This invention relates to improvements in lamps especially adapted for use in boudoirs and has particular reference to a supporting structure for the lamp.

5 An object of the invention is to provide an improved support for lamps which is of simple, practicable and inexpensive construction, and wherein the removable end members of the body of the lamp are connected by said support in such 10 manner that the elements can be readily assembled and taken apart.

The above and other objects will appear more clearly from the following detailed description when taken in connection with the accompanying drawing which illustrates preferred embodiments of the inventive idea.

In the drawing:

Figure 1 is a plan view, partly broken away and shown in section, of a lamp and its support constructed in accordance with the invention.

Figure 2 is a similar view showing the elements of the lamp and support in partly assembled positions.

Figure 3 is an end elevation of the lamp and support as shown in Figure 1, and

Figure 4 is a similar view of a slightly modified form of support.

The support of the present invention is particularly applicable to lamps such as may be used in boudoirs for attachment to bedsteads and other similar supports and, as shown, the lamp includes an elongated cylindrical body 5 the ends of which are open and slightly reduced in diameter. The body 5 may be of translucent glass and fluted for decorative purposes and is adapted to receive therein a source of light 7 such as an incandescent lamp.

When the lamp is assembled, the open ends of the body 5 are closed by removable end members 40 8 and 9 in the form of metallic caps of cup shape fitting over the reduced ends 6 of the body and onto the adjacent main portion thereof. The cap 9 has a socket 10 therein in which the lamp 7 is mounted in the usual manner, and projecting from the end of the cap is a switch 11 of conventional construction by means of which said lamp may be turned on and off.

The support and its means of attachment to the lamp elements will now be described.

50 Said support is utilized to interconnect the caps 8 and 9 and, for this purpose, the latter are provided with internally threaded bushings 12 extending from the peripheral portions thereof. A connecting member 13 in the form of an elongated metallic strap has its ends 14 and 15 offset

from the intermediate portion thereof and these ends are connected to the bushings 12 in the following manner. The end 14 is placed upon the bushing 12 on the cap 9 with a washer 16 of larger diameter than the bushing interposed between the latter and said end; and a fastening screw 17 is then extended through an opening in said end and threaded into the bushing to pivotly connect the strap 16 to said cap. With the lamp 7 mounted in its socket 10, one end of the body 5 may now be inserted into the cap 9, and, with the strap 13 extending longitudinally of the body, the cap 8 is mounted upon the other end of said body. The bushing 12 of the latter cap also has a fastening screw 18 threaded therein with a washer 19, similar to the washer 16, resting upon said bushing. When placing the cap 8 in position, it is turned circumferentially until the screw 18 is aligned with a slot 20 in the adjacent end 15 of the strap so that the shank of the screw will enter said slot when the cap is moved inwardly upon the end of the body 5. The screws 17 and 18 may then be tightened to securely connect the caps 8 and 9 with the body 5 therebetween and, if desired, said screws may be of such length that when the same are tightened the inner ends thereof will engage the reduced ends 6 of the body and prevent any shifting in a rotatory direction.

To mount the lamp upon a suitable support, 30 such as indicated at 21, the strap 13, as shown in Figures 1 and 3, has secured thereto at the ends of its intermediate portion a pair of angular, inserting U-shaped brackets 22 the side arms of which are adapted to receive the support 21 there- 35 between and in one of the arms of each bracket a headed clamping screw 23 is threaded so that the head of the screw will engage the back of the support to clamp the device in position. When thus disposed, the intermediate portion of the strap 40 13 will rest against the support and, by reason of the offset ends 14 and 15 of said strap the body of the lamp will be spaced from said support, thus providing a clearance which will prevent contact of the heads of the screws 17 and 45 18 with the adjacent surface of the support 21.

- As shown in Figure 4, the strap 13 has secured thereto in any preferred manner one end of a curved bracket 24 which may be covered with a rubber sleeve or tubing 25 to protect the surface of the support upon which the lamp may be mounted.

What is claimed is:

1. In a lamp, the combination of a light permeable body adapted to enclose a source of light. 55

removable end caps for said body, a connecting member joining said end caps and having its ends offset from the intermediate portion thereof, with one of said ends provided with a slot 5 open at the adjacent extremity of said connecting member, means to secure the other end of said connecting member to one of said caps, a fastener extending through the slot in the first 10 named end of the connecting member and into the associated end cap, and means on said strap for mounting the lamp on a support.

2. In a lamp, the combination of a cylindrical open ended light permeable body adapted to enclose a source of light, end caps fitting over the 15 ends of said body to close the same, bushings

protruding from said end caps, a connecting strap for said end caps having offset ends one of which has an opening and the other a slot, a fastener extending through said opening and adjacent cap and into the bushing carried thereby, 5 another fastener extending through the slot in the other end of said strap and into the bushing of the second cap, said fasteners and strap cooperating to maintain said caps in position on the ends of said body, and brackets on said strap 10 for mounting the lamp in position on a support, the intermediate portion of said strap engaging said support to space said body and fasteners therefrom.

MAX LAGER. 15
